UNITED STATES PATENT OFFICE.

JOHAN M. ANDERSEN, OF BOSTON, MASSACHUSETTS, ASSIGNOR TO ALBERT & J. M. ANDERSON MANUFACTURING COMPANY, OF BOSTON, MASSACHUSETTS, A CORPORATION OF MAINE.

TIME CIRCUIT-CONTROLLER.

1,299,812.

Specification of Letters Patent.

Patented Apr. 8, 1919.

Application filed January 20, 1917, Serial No. 143,514.

To all whom it may concern:

Be it known that I, JOHAN M. ANDERSEN, a citizen of the United States, and a resident of Boston, in the county of Suffolk and State of Massachusetts, have invented 5 an Improvement in Time Circuit-Controllers, of which the following description, in connection with the accompanying drawings, is a specification, like characters on the 10 drawings representing like parts.

This invention relates to time circuit controllers, substantially of the character shown and described in U. S. Patent No. 779249 granted to me January 3, 1905, and has for 15 its object to provide a simple and inexpensive construction of apparatus, which is especially designed and adapted for operating a circuit controller having a rotatable member, whereby a small, compact, and sub- 20 stantially inexpensive apparatus may be obtained.

The particular features of the invention will be pointed out in the claims at the end of this specification.

25 Figure 1 is a front elevation of an apparatus embodying this invention, the door of the casing being shown open.

Fig. 2, a rear elevation of the apparatus removed from its casing.

30 Fig. 3, a side elevation of the apparatus looking toward the left in Fig. 2, and

Fig. 4, a detail to be referred to.

Referring to the drawings, *a* represents the back plate and *b*, the front plate of a 35 frame work for supporting the operative parts of the apparatus.

The time element of the apparatus comprises a clock mechanism having a main spring 10 located in a barrel or drum 12, 40 provided at one end with a gear 13 and closed at its other end by a gear 14, which latter is fast on the shaft 15 upon which the barrel 12 is loosely mounted. The rotation of the main shaft 15 by spring 10 is 45 controlled in the usual manner by a train of gears 16, which is connected with the gear 14 by a pinion 17 on a shaft 18.

The shaft 15 has fast on it the toothed disk or gear wheel 20, provided with radial 50 slots 21 with which coöperate bent fingers on levers 22, 23, which form with the disk 20 a selective mechanism for determining the time at which a rotatable member should operate.

55 The levers 22, 23, are fast on concentric

shafts or sleeves, not shown, but similar to those shown in the patent referred to and which are extended through the front and rear plates of the framework and have fast on them tripping dogs 25, 26, which co- 60 operate with a finger 27 on the arm 28 of a lever 29, to render the main spring 10 of the clock mechanism effective to operate the rotatable member referred to.

In the present instance the rotatable member referred to comprises two hubs 30, 31, mounted on a shaft 32 to rotate therewith and provided with a plurality of sets of contact arms 33, 34, which coöperate with a plurality of pairs or sets of circuit terminals or stationary contact arms 35, 36, which are attached to suitable supports 37 forming part of a rotary switch of known construction.

The hub 31 has attached to it a disk 38 75 having thereon the words "On" and "Off", which coöperate with an opening 39 in a cover 40 for the switch, and which cover is exposed to view when the door 41 of the casing or box 42 is open as represented in 80 Fig. 1.

The rotatable shaft 32 of the switch is extended through the back plate *a* and is supported by a cross bar 43 attached to the back plate *a*, and said shaft has fast on it 85 a substantially large gear 44, which meshes with a smaller gear 45 mounted on a shaft 46 supported by the front and back plates *a*, *b*, and provided with a pinion 47, which meshes with the gear 13 fast on the barrel 90 12. The gear 45 is normally loose on the shaft 46 but is secured thereto to rotate therewith when the shaft 46 is rotated in one direction by the main spring 10, but is connected with the shaft 46 in such manner 95 as to permit the said shaft to be turned in the opposite direction, in order to wind up the main spring 10, without rotating the gear 45. The connection between the gear 45 and the shaft 46 is effected as herein 100 shown by a clutch member, which is shown as a disk 50 having ratchet teeth 51, see Fig. 3, which mesh with like ratchet teeth on the hub of the gear 45.

The ratchet disk 50 is mounted to slide 105 on a sleeve 53, secured to the shaft 46 to rotate therewith by a pin 55 or otherwise, and said ratchet disk is keyed to the sleeve 53 so as to rotate therewith and to slide thereon, and is normally held in engagement 110

with the ratchet teeth on the hub of the gear 45 by a spring 56, encircling the said sleeve between a collar 57 thereon and the ratchet disk 50.

5 It will thus be seen that when the main spring 10 is permitted to act as will be described, so as to rotate the shaft 46, the clutch member 50 fast thereon will couple the gear 45 to the said shaft, so that the said 10 gear rotates with the shaft 46, and the rotation of the gear 45 effects rotation of the large gear 44, its shaft 32 and the movable contact member or members 33, 34 of the rotary switch. When, however, the shaft 15 46 is turned in the opposite direction to wind up the spring 10, by a suitable key, not shown, but which is applied to the end of the shaft 46 at the front of the framework, and shown in Fig. 1, the ratchet teeth of 20 the clutch member 50 click by the ratchet teeth on the hub of the gear 45 and the latter is not rotated, consequently the position of the movable contact member of the switch is not changed.

25 The main spring 10 drives the selective mechanism 20, 22, 23 continuously, and drives the switch operating gears 45, 44 intermittently, and provision is made for normally rendering the spring ineffective to 30 rotate the gearing which rotates the switch member. This result is accomplished as herein shown by mechanism interposed between the gear 45 and the tripping dogs 25, 26, and in the present instance comprises a 35 disk 60 mounted on the hub of the gear 45 and connected to the latter to rotate therewith, said disk being provided in the present instance with substantially diametrically opposite lugs or projections 61, 62, which 40 coöperate with a finger 63 on a detent lever 64, which is pivoted to the back plate *a* of the framework and is operatively connected by a pin and slot connection 65, 66, with the lever 29, which latter may be referred to as 45 the escape or release lever.

The release lever 29 is acted upon by a 50 spring 70, which serves to move the said lever and normally place the finger 27 into the path of movement of the tripping dogs, and to turn the detent lever 64 so as to normally bring the finger 63 thereon into the path of rotation of one of the projections on the disk 60. When the tripping dogs are 55 out of engagement with the finger 27, the finger 63 on the detent lever 64 is in the path of movement of the lugs 61, 62 on the disk 60, and as shown in Fig. 2, the lug 61 is in engagement with the finger 63 and the disk 60 is held from rotating. As a result, 60 the end of the main spring 10 of the clock mechanism which is connected with the barrel 12, is stationary or anchored, while the end connected with the gear 14 is free to drive the clock mechanism and the selective mechanism,

At the proper time, the clock brings one of the tripping dogs into engagement with the finger 27 on the release lever 29, and on the continued movement of the tripping dogs, the lever 29 is turned from substantially the position shown in Fig. 2 to that shown in Fig. 4 so as to remove the finger 63 on the detent lever 64 from engagement with the lug 61, whereupon the main spring 10 becomes active to rotate the disk 60. The 70 release lever 29 is normally out of the path of movement of the lugs 61, 62 on the disk 60, and is brought into said path when the finger 63 is removed from said path, so that the disk 60 and gear 45 are rotated only a 75 short distance before being arrested by the arm 67 of the lever 29, see Fig. 4, which arm is removed from the path of movement of the lugs 61, 62, as soon as the tripping dog 25 or 26 passes out of engagement with the finger 27 and permits the spring 70 to move the release lever 29 back into its normal position, shown in Fig. 2, in which a pin 72 on its arm 28 is engaged with a stud 75 on the back plate *a*. The release lever 29 on 80 its return movement under the influence of the spring 70, turns the detent lever 64 into its normal position so as to move the finger 63 into the path of movement of the lug 62. When the finger 63 is disengaged from the 85 arm 67 of the lever 29, the disk 60 and gear 45 are free to be rotated substantially a half turn by the spring 10, until the lug 62 is engaged with the finger 63 of the detent lever 64.

The gear 45 rotates the gear 44 and in the present instance these gears are proportioned so that a half revolution of the gear 45 effects a quarter revolution of the gear 44 and of the contact members 33, 34 attached to the 90 shaft 32. The disk 60 and gear 45 are rotated quite rapidly by the spring 10 when the finger 63 and lever 29 release the lug 61 or 62 with which they are engaged, and the said lugs strike the finger 63 on the detent 95 lever 64 a substantially severe blow, and to avoid danger of the finger 63 being broken off by repeated blows upon it, which would render the apparatus inoperative if permitted to occur, provision is made for cushioning the blow, and this result is effected as herein shown, by providing a spring connection between the disk 60 and the gear 45. To this end, the disk 60 is provided with substantially diametrically opposite slots 100 located adjacent to the lugs 61, 62, and through which are extended pins 83 attached to the gear 45, which pins are connected by springs 84 with pins 85 on the disk 60.

The springs 84 serve to hold one end of 105 the slots 80 in engagement with the pins 83, so that when the lugs 61, 62 strike the finger 63, the disk 60 can be moved backward so as to diminish the force of the blow upon the 110 said finger.

Provision is also made for manually releasing the detent lever 64 from the disk 60, and to this end I employ a reciprocating rod 86, which is provided as shown with an 5 end portion 87 of reduced diameter, which slides in a hole extended through the stop pin 75 and is adapted to engage the stud or pin 72 on the release lever 29. The opposite end of the rod 86 is pivotally connected to 10 one arm of an elbow lever 90, which is pivoted to a stud or post 91 on the back plate *a* and has its other arm pivotally connected with the end of a push rod 92, extended through the back and front plates of the 15 framework and provided at its front end with a suitable head or thumb piece 93.

By reference to Figs. 2 and 3, it will be seen that the operator by pushing upon the thumb piece 93 moves the rod 92 so as to 20 turn the lever 90 in one direction and move the rod 86 in the direction of the arrow 94, Fig. 2, and cause the reduced end 87 of the rod to engage the pin 72 and turn the release lever 29 so as to disengage the finger 63 25 from the lug 61 and enable the spring 10 to turn the disk 60, so that the lug 61 engages the lever 29, and as soon as the operator removes his thumb or finger from the head 93 of the push rod, a spring 95 which encircles 30 the reduced portion 87 of the rod 86 acts to move the latter back to its normal position shown in Fig. 2, and allows the spring 70 to restore the release lever 29 and the detent lever 64 to their normal positions, thereby 35 disengaging the lever 29 from the lug 61 and permitting the spring 10 to rotate the gear 45 and disk 60 a half turn, so as to either open or close the switch according to what position the switch is in when the push rod 40 92 is operated.

When the switch is under the influence of the clock, the tripping dogs 25, 26 automatically perform the same function as the rod 86. The tripping dogs 25, 26, are properly positioned with relation to the finger 27 of the release lever by the hands or arms 22, 23, which are turned with relation to the toothed disk 20 by the operator and locked to said disk by the fingers on the said arms 50 entering selected slots 21 in the face of the disk 20, so that the clock will automatically open and close the switch at the selected or desired hours, as more fully described in the patent referred to.

55 I have herein shown one construction of apparatus embodying this invention but it is not desired to limit the invention to the particular construction shown.

Claims:

60 1. In an apparatus of the character described, in combination, a clock mechanism having a main spring, a main shaft to which one end of the said spring is connected to rotate said shaft, a gear fast on said main shaft, a second gear loose on said main shaft 65 and with which the opposite end of said spring is connected, a pinion in mesh with said loose gear, a winding shaft on which said pinion is mounted, a gear loosely mounted on said winding shaft, a clutch to render 70 said gear fast on said winding shaft, a rotatable switch member, a gear connecting the latter with the gear on the winding shaft, a disk movably connected with the gear on said winding shaft and provided 75 with a lug, a lever having a finger coöperating with said lug, a second lever connected with the first mentioned lever to actuate the same and disengage said finger from said lug, a tripping dog coöperating with said 80 second mentioned lever, a slotted disk fast on said main shaft, and an arm connected with said tripping dog and provided with a finger to enter a slot in said slotted disk. 85

2. In an apparatus of the character described, in combination, a clock mechanism provided with a main spring, a gear connected with one end thereof, a pinion in mesh with said gear, a winding shaft on which said pinion is mounted, a gear loosely mounted 90 on said winding shaft and provided with a hub having ratchet teeth, a clutch member mounted on said shaft to rotate therewith and to slide thereon and provided with ratchet teeth coöperating with the ratchet 95 teeth on said hub, a spring to normally keep said clutch member in engagement with said hub, a disk loose on said hub and provided with a slot, a pin extended through said slot and attached to said gear, a pin on said disk, 100 a spring connecting said pins, a lug on said disk, a detent lever having a finger coöperating with said lug, a release lever connected with said detent lever, and a selective mechanism coöperating with said release lever 105 and actuated by the main spring of said clock mechanism.

3. In an apparatus of the character described, in combination, a main spring, a device rotated thereby, a detent lever co- 110 operating with said device, a release lever co-operating with said detent lever, a reciprocating rod coöperating with said release lever to actuate the detent lever and permit the main spring to rotate said device, an 115 elbow lever having one arm pivotally connected with said reciprocating rod, and a second reciprocating rod pivotally connected with the other arm of said lever.

4. In an apparatus of the character described, in combination, a main spring, a device rotated thereby, a detent lever coöperating with said device, a release lever coöperating with said detent lever to actuate the latter and engage and disengage it with and from 125 the said device, a reciprocating rod coöperating with said release lever to move it and thereby actuate the detent lever and permit the main spring to rotate said device, a manually operated rod extended substan- 130

tially at right angles to said reciprocating rod and connected with the latter to reciprocate it.

5. In an apparatus of the character described, in combination, a clock mechanism having a main spring and a time train operatively connected with one end of said spring and governing the action of said main spring, a selective mechanism operatively connected with the same end of said main spring to be driven thereby, a gear connected with the other end of said main spring to be rotated by the said main spring, a circuit controller provided with a rotatable member, gearing for connecting said rotatable member with the gear driven by the main spring of said clock mechanism, means coöperating with said gearing to restrain the same from being driven by one end of said main spring while the other end thereof is driving the said selective mechanism, and means operated by said selective mechanism to release said gearing from restraint and permit the latter to be rotated by the said main spring.

6. In an apparatus of the character described, in combination, a clock mechanism having a main spring and a time train governing the action of said main spring, a selective mechanism operatively connected with one end of said main spring to be driven thereby, a gear connected with the other end of said spring to be rotated by the said main spring, a circuit controller provided with a rotatable member, gearing for connecting said rotatable member with the gear driven by the main spring of said clock mechanism, means coöperating with said gearing to restrain the same from being driven by one end of said main spring while the other end thereof is driving the said selective mechanism, and manually operated means for releasing said gearing from restraint and permit the latter to be rotated by the said main spring.

7. In an apparatus of the character described, in combination, a rotatable switch member, a clock mechanism provided with a main spring, a main shaft to which one end of the said spring is connected, to be rotated thereby, and a time train geared with said main shaft and governing the action of said main spring, gearing for connecting said rotatable switch member with the other end of the said main spring to be operated thereby, means coöperating with said gearing for restraining said main spring from rotating said switch member, a selective mechanism mounted on the main shaft of said clock mechanism to rotate therewith, and a releasing device for said restraining means operated by said selective mechanism to permit the main spring of said clock mechanism to effect rotation of said switch member.

8. In an apparatus of the character described, in combination, a rotatable switch member, a clock mechanism provided with a main spring, a main shaft to which one end of the said spring is connected, to be rotated thereby, and a time train geared to said main shaft and governing the action of said main spring, gearing for connecting said rotatable switch member with the other end of the said main spring to be operated thereby, means coöperating with said gearing for restraining said main spring from rotating said switch member, a selective mechanism mounted on the main shaft of said clock mechanism to rotate therewith, a releasing device for said restraining means, and manually operated means coöperating with said releasing device to mechanically operate the latter.

9. In an apparatus of the character described, in combination, a clock mechanism provided with a main shaft and with a main spring having one end connected with said main shaft, a time train to govern rotation of said main shaft, a gear fast on said main shaft, a second gear loose on said main shaft and with which the other end of the main spring is connected, a rotatable device, gearing for connecting said rotatable device with the gear loose on said main shaft, a clutch mechanism forming part of said gearing for enabling the rotatable device to be rotated by said main spring and for enabling the gear loose on the main shaft to be rotated to wind up the spring without rotating the said rotatable device, means for restraining said main spring from rotating said device, a releasing device for said restraining means, and a selective mechanism mounted on said main shaft to rotate therewith and coöperating with said releasing device.

10. In an apparatus of the character described, in combination, a clock mechanism provided with a main shaft and with a main spring having one end connected with said main shaft, a time train geared to said main shaft and governing rotation thereof, a gear fast on said main shaft and connected with said time train, a gear loose on said main shaft and with which the other end of said main spring is connected to be driven by said main spring, a rotatable device, gearing connecting said rotatable device with the gear loose on said main shaft, means for restraining said main spring from rotating said device, means for releasing said restraining means, and a selective mechanism driven by said main shaft and coöperating with said releasing means.

11. In an apparatus of the character described, in combination, a main spring, a device rotatable thereby, a detent lever coöperating with said device to restrain it from rotating, a release lever connected with said detent lever to turn the latter into operative

and inoperative relation to said rotatable device and itself movable into operative and inoperative relation to said rotatable device when the detent lever is moved into its inoperative and operative positions with relation to said rotatable device, said release lever acting to engage said device and re-

strain it from rotating after it has been released by the detent lever, and a tripping dog for operating said release lever.

10

In testimony whereof, I have signed my name to this specification.

JOHAN M. ANDERSEN.
